UNITED STATES PATENT OFFICE.

FRANCIS JOSEPH BATCHELDER, OF NEW YORK, N. Y.

DESIGN FOR A GAME-BOARD.

49,136.

Specification for Design.

Patented June 6, 1916.

Application filed April 3, 1915. Serial No. 19,081. Term of patent 3½ years.

To all whom it may concern:

Be it known that I, FRANCIS JOSEPH BATCHELDER, a citizen of the United States, residing at New York city, county and State of New York, have invented a new, original, and ornamental Design for Game-Boards, of which the following is a specification, reference being had to the accompanying drawing, forming part thereof.

The figure is a plan view of a game board, showing my new design.

I claim:

The ornamental design for a game board, as shown.

FRANCIS JOSEPH BATCHELDER.

Witness:

W. R. WARNER.
